UNITED STATES PATENT OFFICE.

WILLIAM H. BANFIELD, OF IRONDALE, OHIO.

CLEANING AND SCOURING HOT ROLLS.

SPECIFICATION forming part of Letters Patent No. 511,493, dated December 26, 1893.

Application filed December 8, 1892. Serial No. 454,495. (No model.)

To all whom it may concern:

Be it known that I, WILLIAM H. BANFIELD, a resident of Irondale, in the county of Jefferson and State of Ohio, have invented a new 5 and useful Improvement in Cleaning and Scouring Hot Rolls; and I do hereby declare the following to be a full, clear, and exact description thereof.

My invention relates to the cleaning or 10 scouring of hot rolls, that is, of rolls for rolling sheet or plate metal to which particles of scale, oxide, or others such matters, adhere and are pressed into the surfaces of the metal passing between the rolls so as to form rough surfaces thereon. These particles of metallic oxide gather in innumerable quantities on 15 the surfaces of the rolls, and, though recognized as a difficulty which it is desired to overcome, the rolls have been used with such oxide adhering thereto because no proper means 20 for scouring the rolls when hot was provided. Such rolls have been scoured when cold by means of suitable devices adapted to press the emery or scouring material against the 25 same, but that required the cooling down of the rolls which occupied a day or more and a subsequent re-heating of the rolls, which could only be done by the passing of plates or sheets through, the plates or sheets so formed being 30 either of poor quality or, in some cases, so imperfect that they could not be used commercially, and a loss of at least two days being occasioned at each time that said rolls 35 were scoured when cold. It is therefore evident that a means for scouring these rolls when hot is very desirable, and the object of my invention is to provide such means.

To these ends my invention consists, generally stated, in driving each roll by power 40 and inserting between the rolls a suitable non-combustible support for the grinding material, itself protected so as to prevent the burning of the body thereof by the heat of the rolls, and by such support holding the 45 grinding or scouring material up against the roll faces, it being found that the rolls can be properly scoured in this way even at the ordinary heat at which they are best suited for rolling the plates or sheets, and that no time

further than that occupied in scouring need 50 be lost in the operation of the rolls.

It also consists in certain improvements in the devices employed.

To enable others skilled in the art to practise my invention, I will describe the same 55 more fully, referring to the accompanying drawings, in which—

Figure 1 is a sectional view of a set of rolls illustrating the scouring operation. Fig. 2 is an end view thereof, and Fig. 3 is a perspective 60 view of the scouring device embodying my invention. Fig. 4 is an enlarged view showing the rolls and scouring device. Figs. 5 and 6 are detail views of the pinion and connection.

Like letters of reference indicate like parts 65 in each.

The rolls illustrated in the drawings are the ordinary two high sheet rolls, these rolls, under ordinary circumstances, driven, the one by power and the other by friction, it being 70 found that a more even rolling operation can be thus produced. These rolls gather on their faces the particles of iron oxide, scale, &c., above referred to, the same being held thereto in minute particles, such as in pin 75 points, or in small grains or atoms, the whole mass of the rolling surface being covered with such particles after the rolls have been used for a considerable time. In order to arrange the rolls for the scouring thereof in 80 accordance with my invention, I provide suitable gearing connecting the two rolls, as shown in Fig. 2. In said figure *a* is the housing, *b* the upper roll, *c* the lower roll, and *d* the adjusting screws by which the upper roll is ad- 85 justed upon the lower roll, the lower roll being generally driven by suitable connections from the engine. When the rolls are to be scoured, I place upon the upper roll a suitable pinion *e* gearing with a pinion face *f* 90 connected to the lower roll, such as on the coupling collar *f'*, or place such pinions *e* and *f* upon both rolls, so as to drive them together. In the drawings this pinion *e* is provided with curved cheeks *e'* projecting from it and en- 95 gaging with the wabbler of the roll, the pinion being secured to the wabbler by a bolt *e*.

For the grinding operation the upper roll is

raised to some extent, so that it will be driven without contact with the other.

For the purpose of supporting the grinding and scouring materials, I provide the scouring wedge *g*, which is more clearly shown in Fig. 3, that wedge having the tongue *h* which passes between the two rolls to properly support the scouring wedge in place, and above said tongue the curved faces *k* which conform 10 approximately to the curve or circle of the rolls; the wedge having the handle *l* for manipulating the same. This wedge is preferably formed of wood, or like fibrous material, which, if subjected to heavy strain, will be 15 simply crushed without fear of accident by the flying of the parts thereof. The wood has also the further advantage of being a non-conductor when properly protected, and so holding the heat up to the roll surfaces, which 20 assists in scouring. At the heat at which the rolls are heated, however, in connection with the friction between the scouring wedge and rolls, the wooden wedge would soon ignite. To prevent this, I provide it with a sheet 25 metal covering on the surfaces exposed to the frictional action, such covering being shown at *m* around the tongue *h* and along the curved faces *k*. Such covering also preferably extends up over the body portion *n* of 30 the wedge. This metallic covering *m* forms the supporting face for the scouring material, which is preferably formed of emery, or other proper scouring or grinding granular material, mixed with a roll-grease capable of with- 35 standing a high heat. Such greases are now made to withstand the heat of the roll without ignition, and therefore form a proper substance for holding the emery to place. They are known as hot neck grease. Such hot neck 40 grease and emery are properly intermingled to form the scouring compound.

In practicing the invention, the wedge is coated with a compound of this roll-grease and emery which is laid in a thick coating upon the 45 metallic covering *m* along the curved faces *k* and the faces of the wedge *g*, and when it is desired to scour the rolls they are geared together in the manner above described, the upper roll is loosened so as to permit the insertion 50 of the wedge, while the rolls are driven at the proper speed, practically the speed at which the mill is run, the wedge is inserted between the rolls and the curved faces carrying the scouring material brought up against 55 the same so as to act to scour the rolls while in the heated condition at which they had been employed in rolling the metal. The operator moves the scouring wedge along the faces of the rolls, applying such pressure as 60 he finds proper for the purpose, the tongue *h* of the wedge supporting the same in position so that the only requirement is for the operator to apply the proper force for scouring and to move the scouring wedge along so as 65 to cause the scouring and cleaning of the en-

tire surface of the rolls. In such operation it is evident that if the movement of the rolls is such as would grasp and carry any wedge, there is practically no danger to the operator, as the only effect would be to crush the wedge 70 itself which is formed of such fibrous material as would not fly or lead to serious accident. At the same time, the heat from the rolls themselves, or created by the friction of the rolls upon the scouring wedge, will not affect 75 the body of the wedge, as the metallic covering *m* interposed between the rolls and such body takes the force of the roll and prevents the ignition of the wood by direct contact of the wedge body with the rolls. This 80 wedge may be formed, if desired, of wrought iron, though such material is not considered as desirable as the wood, as in case the wedge were drawn within the roll, though the wrought metal wedge would not be so liable to fracture as a cast metal wedge, yet it would be liable to injure or break the rolls and would be more quickly heated by conduction, which might affect the action of the scouring materials upon the rolls. The wooden wedge 85 would, of course, be crushed if caught with and carried into the rolls, and no injury would occur to the rolls themselves.

During the scouring operation the materials for scouring, that is, the compound containing emery, may be replenished, as found necessary, or the emery may be added to the supporting material so as to cause a proper and even scouring of the rolls. It is found by practical use that by this means the rolls 90 can be quickly and evenly scoured, while at the same heat at which they are most successfully employed for the rolling of metal, and that the only time necessarily consumed is that of gearing the rolls together and scouring 95 them by means of the compound applied by the wedge, after which operations the rolling can be proceeded with at once. It is found that by such means all these small particles of metallic oxide, or other such materials, can be entirely removed from the rolls, and the clean metallic surface desirable for 100 rolling be again exposed.

What I claim as my invention, and desire to secure by Letters Patent, is— 105

1. The herein-described method of scouring rolls for rolling metal when the same are heated, consisting in driving both rolls by power connections and inserting between them a suitable non-combustible support and thereby holding the scouring materials against the faces of the rolls, substantially as set forth.

2. A scouring device for rolls, consisting of a suitable block having a non-combustible face and curved corresponding to the roll face, and adapted to hold the scouring material against the same, substantially as set forth.

3. A scouring device for rolls, consisting of a wedge block having a tongue extending out 130

therefrom and adapted to pass between the rolls, and curved scouring faces at the base of said tongue, said wedge block having a non-combustible face to contact with the roll faces, substantially as set forth.

5 4. A scouring device for rolls, formed of wood, and having a curved face corresponding to the roll face, such curved face hav-

ing a metallic covering, substantially as set forth.

In testimony whereof I, the said WILLIAM H. BANFIELD, have hereunto set my hand.

WM. H. BANFIELD.
